(74) *Attorney, Agent, or Firm* — Design IP

CLAIM

The ornamental design for a dough proofing tray, as shown
and described.

DESCRIPTION

FIG. 1 is a perspective view of a dough proofing tray
showing our new design;
FIG. 2 is a front view thereof;
FIG. 3 is a rear view thereof;
FIG. 4 is a left side view thereof;
FIG. 5 is a right side view thereof;
FIG. 6 is a top view thereof; and,
FIG. 7 is a bottom view thereof.

(Continued)

The broken line showing of portions of the dough proofing tray in FIGS. 1-7 represents environmental subject matter and forms no part of the claimed design.
